(57) CLAIM

The ornamental design for an autonomous vehicle, as shown and described.

DESCRIPTION

FIG. 1 is a front view of an autonomous vehicle in accordance with the present design;

FIG. 2 is a rear view thereof;

FIG. 3 is a side elevational view thereof;

FIG. 4 is a top elevational view thereof;

FIG. 5 is a rear perspective view thereof; and,

FIG. 6 is a front perspective view thereof.

The broken lines depict portions of the autonomous vehicle that form no part of the claimed design.
